UNITED STATES PATENT OFFICE.

LA FAYETTE JOHNSON, OF ST. JOSEPH, MISSOURI.

UNION SUIT.

1,187,620.

Specification of Letters Patent. Patented Apr. 23, 1915.

Application filed May 2, 1914. Serial No. 835,613.

To all whom it may concern:

Be it known that I, LA FAYETTE JOHNSON, a citizen of the United States, residing at St. Joseph, in the county of Buchanan and State of Missouri, have invented certain new and useful Improvements in Union Suits; and I do hereby declare the following to be a full, clear, and exact description of the invention, such as will enable others skilled in the art to which it appertains to make and use the same.

This invention relates to combination or union-suits and has particular reference to that type of such garments as relate to the manufacture of the upper or outer shirt from the same piece of goods used in the making of the under garments or drawers.

As a particular object, this invention contemplates the provision of a negligée shirt manufactured in one continuous piece, with the under garments or drawers and which is provided with means for forming a reliably closed crotch.

A still further object is to provide a union-suit or combination garment of the type described which shall disclose means coacting with an opening made in the rear portion of the under garment which shall provide a reliably closed crotch and at the same time allow for an easy opening of the same when such is desired.

The above and additional objects which may hereinafter be discerned in the following specification will accomplish such means as are illustrated in the accompanying drawings, described in the following specification and then more particularly pointed out in the claims which are appended hereto and form a part of this application.

With reference to the drawings, wherein I have illustrated the preferred embodiment of my invention as it is reduced to practice, and throughout the several views of which like characters of reference designate similar parts in which—

Figure 1 is a front elevational view of an approved form of my garment and, Fig. 2 is a rear elevational view disclosing the opening form in the rear of said garment and the means for normally holding the same closed.

Proceeding now to the description of the drawings it will be seen that the front portion 5 of my garment consists of the two similar but oppositely disposed gores or side pieces 6 and 7, the latter of which over laps

the former and has means such as the buttons 8 by which it is removably connected thereto. The back portion of my garment is composed of the breadth 9 and the leg pieces 10 and 11 which are connected to the breadth 9 by means of the gusset 12. The leg piece 11 is sewed, stitched or otherwise secured to the gore 6 of the front portion 5 along the seams indicated at 13 and the leg piece 10 is similarly secured to the front gore 7 along the seams indicated by the numeral 14. The outside seams 13 and 14 are continued upwardly to the armholes 15 formed by suitable cut out portions in the front and back of my garment and also serve as the connecting seams between the upper portion of the gores 6 and 7 composing the front 5, with the back breadth 9. The usual shoulder gusset 16 shown in the front 5 and the back 9, above the armholes 15 and the customary collar band 17, is stitched in the usual position upon the upper part of my garment connected to the side gores 6 and 7. The customary sleeves 18, are adapted to the sides of the armholes 15 and terminate in the ordinary cuffs 19.

Turning now to the more specific portion of my invention, it will be seen that I have provided a reliably closed crotch which is removably so held by the following means. The leg pieces 10 and 11 are not stitched together or secured along their meeting edges at the rear portion of the garment, but loosely overlap each other. The flap piece 20 is stitched or suitably secured to the leg piece 10, along the seam 21 and serves as a closing portion for the opening thus created. As means for normally securing this flap portion 20 to the leg piece 11, I provide the button of similarly securing means 22, but have also found it highly desirable to provide the pieces of elastic web or tape 23 and 24, the former of these being secured at one end to the gusset 12 at the right of the medial line of the garment and at the other to the flap 20 and as will readily be seen serves to hold this flap portion smooth over the opening. The webbing 24 is also secured at one end to the gusset at the left of the medial line of the garment and at the other to the free side of the leg piece 11, this piece of webbing being positioned under the flap 20 and the leg piece 10 as will readily be understood by referring to the drawings. It will thus be seen that to open the rear portion of the under garment the wearer has but to

unfasten the button 22 and to pull back the flap 20 against the tension of the webbing and then immediately such pulling section ceases that the flap 20 will be returned to place by the webbing and will be additionally so held by refastening the button 22.

It is of course to be understood that should it be desired to make the shirt portion of my combined garment of a different material than that used in the drawers thereof, that this may be done very readily without effecting the closed crotch as herein disclosed and the elastic means provided for the closing thereof. In this connection it may be noted further that the drawers which have been here shown of knee length may be made ankle length or any intermediate length considered desirable.

While in the foregoing I have illustrated in the drawings and described in the specifications, such combination and arrangement of elements as constitute the preferred embodiment of my invention, I desire to emphasize the fact that I may make such minor changes in the matters of proportion and degree, in later adaptations of my device as shall not alter the spirit of my invention as defined in the appended claims.

What I claim is:

1. In a union garment combining a negligée shirt and a pair of drawers, a practically closed crotch provided for the latter including a flap portion normally closing an opening formed in the rear of said drawers; resilient means for connecting the detached edge of the flap to the right side of the body portion; other resilient means for connecting the free edge of the right leg to the left side of the body portion of the said garment, whereby the parts of the crotch are automatically held in closed relation. 35

2. In a combination set including upper and lower garments and an opening formed in the rear portion of said lower garment, a flap piece overlapping said opening and elastic webbing pieces for normally holding said flap portion and the free edge of the right leg over said opening thereby closing the latter. 40

In testimony whereof I have signed my name to this specification in the presence of two subscribing witnesses.

LA FAYETTE JOHNSON.
